UNITED STATES PATENT OFFICE.

CARLYLE W. THOMAS, OF BRIDGEPORT, CONNECTICUT, ASSIGNOR TO THE SINGER MANUFACTURING COMPANY, A CORPORATION OF NEW JERSEY.

SEWING-MACHINE CLOTH-PRESSER.

1,234,965.

Specification of Letters Patent. Patented July 31, 1917.

Application filed May 11, 1915. Serial No. 27,294.

To all whom it may concern:

Be it known that I, CARLYLE W. THOMAS, a citizen of the United States, residing at Bridgeport, in the county of Fairfield and 5 State of Connecticut, have invented certain new and useful Improvements in Sewing-Machine Cloth-Pressers, of which the following is a specification, reference being had therein to the accompanying drawings.

- 10 This invention relates to improvements in cloth-pressers for sewing machines, more particularly that class of devices employed for effecting, at a single operation, the guiding and seaming together of unevenly distributed superposed plies of leather or heavy 15 fabrics, and has for its object to provide a combination of elements adjustable with respect to each other, to the line of seam formation and to the free edges of the material, 20 the cloth-presser being adjustable out of its operative position to permit of the thread-bobbin being removed and replaced in the replenishing of the under thread.

In the accompanying drawings, which 25 form a part of the specification, Figure 1 is a front side elevation of the present improved cloth-presser, together with the front and back slide-plates and a portion of the sewing machine bed-plate into which said 30 slide-plates are mounted, Fig. 2 a plan on the line $x-x$, Fig. 1, Fig. 3 an elevation, partly in full lines and partly in section, of the head of the sewing machine bracket-arm, the cloth-presser and its carrying bar, and 35 the lower end portion of the needle-bar, Fig. 4 a rear side elevation of the present cloth-presser, together with a portion of its carrying bar, Figs. 5, 6 and 7 details later to be referred to, and Fig. 8, one form of 40 product illustrating the application of the present invention.

The present invention is shown in connection with one form of loop-taker mechanism common to Singer sewing machines, and although 45 the present invention is applicable to machines employing only a single needle, it is preferably herein shown and described in connection with a multiple needle machine.

- 50 Referring to the figures, 1 represents the front end portion of a sewing machine bed-plate into which is slidably mounted the front and back slide-plates 2 and 3 respectively, 4 the throat or needle-plate secured 55 to the bed-plate by screw 5, said throat-plate

being provided with needle openings, as 6, and feed-dog openings, as 7, the feed-dog 8 being controlled and actuated by one form of commonly employed four-motion feeding mechanism (not shown). 10 denotes the 60 lower end portion of one form of commonly employed needle-carrying bar provided with a needle-holder 11 into which is suitably secured the needles, as 12, the latter co-operating with the loop-takers, as 13, provided with the under-thread bobbins, as 14, to form stitches.

15 represents a tubular spring-depressed cloth-presser bar mounted at its lower end in a bearing lug 16, (shown in section 70 only, Fig. 3), forming a part of the head 16' of one form of commonly employed overhanging sewing machine bracket-arm (not shown), its opposite end being housed in a bushing 17 threaded into a lug 18, (shown 75 in section only, Fig. 3), formed integral with the upper portion of said head in a manner common to sewing machine construction, said bar being provided with one form of commonly employed lifting lug 19, 80 (shown in section only, Fig. 3), which is acted upon in opposition to the resiliency of the spring 20 by one form of commonly employed lifting lever 20' to raise the cloth-presser out of engagement with the work 85 being stitched.

21 represents a cloth-presser carrying bar mounted in the tubular cloth-presser bar 15 and at its lower end provided with an enlarged portion 22 slotted to receive the 90 shank 23 of the cloth-presser bracket 24, a screw 25 acting to secure said bracket against accidental displacement, and into said enlarged portion is threaded a stud-screw 26 which normally registers with a 95 V-shaped notch 27 in a pinch collar 28 carried by said cloth-presser bar. 29 denotes a screw threaded into the upper end of the cloth-presser carrying bar and between the head of said screw and the upper end of said 100 cloth-presser bar is interposed a spring 30, thus permitting, at the will of the operator, vertical movements of the cloth-presser carrying bar independently of the vertical movements of the cloth-presser bar, for a 105 purpose later to be explained. 31 represents the cloth-presser frame into the front end of which is suitably journaled the cloth-presser rollers 32 and 33 provided with 110 guide-flanges 34 and 35 respectively, the op-

posite end of said frame being provided with a frame-bracket 36 having a groove 37 and an elongated opening 38. 39 denotes a rocking guide-bracket provided with a 5 guideway 40 and fulcrum-pin 41, the latter entering an opening 42 formed in the cloth-presser bracket 24, for a purpose later to be explained.

43 denotes a holding or tightening screw 10 provided with a crank-arm 44 and threaded portion 45 (shown in dotted lines only, Fig. 3) which passes through the opening 38 and threaded into the opening 46 formed in said guide-bracket, the latter being secured 15 against accidental adjustment by the screws, as 47, passing through the elongated opening 48 (shown in dotted lines only, Figs. 1 and 7) formed in the bracket 24 and threaded into the openings, as 49, 20 formed in the bracket 39.

50 and 51 represent stop or registering brackets adjustably secured by screws, as 52, threaded into the cloth-presser bracket 24 for controlling the adjustment of the frame-bracket 36 and cloth-presser frame 31 in opposite directions across the line of seam formation, as shown in full and dotted lines Fig. 1. 53 denotes a needle-guard adjustably secured by screws, as 54, threaded into 25 the openings, as 55, formed in the bracket 24, the wall 56 of the angular portion 57 acting to hold the needles against glancing when entering the materials.

Having set forth the details in construction, the following relative adjustments and coöperation of the parts will be readily understood.

To effect the seaming together of the materials as represented by Fig. 8, the cloth-presser frame 31 first occupies the adjustment shown in full lines Figs. 1 and 4, with 40 one end of the bracket 36 in register with the stop 51 when the plies of materials are positioned beneath the presser-foot with the free edge 58 of the ply 59 in engagement with the flanges 34 and 35 and the feed-dog 9 in alinement with the periphery of said flanges, and owing to the slight incline given the feed-rollers with respect to the upper surface 45 of the needle-plate 4, the feed action of 50 the feed-dog 8, while sufficient to assist in advancing the several plies, will permit of such manual control of the ply 59 as will allow of its free edge being held in guiding 55 relationship with said flanges.

After the double seam 60 has been completed the screw 43 is turned to release the bracket 36, when the latter, together with the cloth-presser frame, is adjusted and secured in dotted line position, Figs. 1 and 4, controlled by the stop 51, when the materials are placed beneath the presser-foot in the same relationship, with respect to the flanges 34 and 35, as when forming the double seam 60 with the feed-dog 8 acting on the mate-

rials between the finished double seam and the line of the double seam 61, the flanges having been adjusted out of effective action with the feed-dog 9, thus permitting such manual control of the materials as is essential to the holding of the free edge 58 in 70 guiding relationship with the flanges.

When it is desired to change the angular relationship of the cloth-presser frame 31 with respect to the upper surface of the 75 needle-plate 4, the operator loosens the screws, as 47, and rocks the guide-bracket 39 on its fulcrum-pin 41 and again secures the guide-bracket, and when it is desired to replenish the under thread the operator by 80 moving the cloth-presser downward in opposition to the resiliency of the spring 30, releases the stud-screw 26 from engagement with the notch 27 in the pinch collar 28 and gives to the cloth-presser carrying bar a 85 half turn, thus carrying the cloth-presser out of vertical alinement with the bobbins, as 14.

Having thus set forth the nature of the invention, what I claim herein is:—

1. In a cloth-presser for sewing machines, the combination with a needle-plate, feed actuating elements, a yieldingly depressed cloth-presser frame supported by the head of the sewing machine bracket-arm and 95 means for giving to said frame vertical movements, of cloth-presser rollers journaled in said frame and at one end only provided with edge guiding flanges to direct the material being acted upon to the action 100 of the stitch-forming mechanism.

2. In a cloth-presser for sewing machines, the combination with a needle-plate, feed actuating elements, a yieldingly depressed cloth-presser frame supported by the head of the sewing machine bracket-arm and means for giving to said frame vertical movements, of cloth-presser rollers journaled in said frame and at one end only 105 provided with edge guiding flanges to direct the material being acted upon to the action of the stitch-forming mechanism, one of said cloth-presser rollers being located in front of and the other at the rear of the line of needle actuation, as viewed by 110 the operator.

3. In a cloth-presser for sewing machines, the combination with a needle-plate, feed actuating elements, a cloth-presser bracket supported by the head of the sewing machine arm, a cloth-presser frame carried by and adjustable laterally with respect to said bracket and means for giving to said frame and bracket vertical movements, of cloth-presser rollers journaled in said frame and provided with edge guiding flanges to direct the material being acted upon to the 120 action of the stitch-forming mechanism.

4. In a cloth-presser for sewing machines the combination with a needle-plate, feed 125

actuating elements, a cloth-presser bracket supported by the head of the sewing machine bracket-arm and carrying a rocking guide-bracket, a cloth-presser frame slidably connected with said rocking guide bracket, means for securing said frame in given adjustment with respect to the latter and to the upper surface of said needle-plate and means for giving to said brackets and frame synchronously arranged vertical movements, of cloth-presser rollers journaled in said frame and provided with edge guiding flanges to direct the material being acted upon to the action of the stitch-forming mechanism.

5. In a cloth-presser for sewing machines, the combination with a needle-plate, feed actuating elements, a resiliently depressed tubular cloth-presser bar mounted in suitable bearings formed in the head of the sew-

ing machine bracket-arm, a cloth-presser carrying bar resiliently suspended in said cloth-presser bar, a cloth-presser bracket carried by said cloth-presser carrying bar and provided with a rocking guide-bracket, 25 a cloth-presser frame connected with the latter and means for giving to said brackets and frame synchronously arranged vertical movements, of cloth-presser rollers journaled in said frame and provided with edge 30 guiding flanges to direct the material being acted upon to the action of the stitch-forming mechanism.

In testimony whereof, I have signed my name to this specification, in the presence 35 of two subscribing witnesses.

CARLYLE W. THOMAS.
